ATTYS.

UNITED STATES PATENT OFFICE.

WILLIAM A. MILES, OF COPAKE IRON WORKS, NEW YORK.

CHARCOAL-KILN.

SPECIFICATION forming part of Letters Patent No. 225,296, dated March 9, 1880.

Application filed September 10, 1877.

To all whom it may concern:

Be it known that I, WILLIAM A. MILES, of Copake Iron Works, Columbia county, New York, have invented new and useful Improvements in Charcoal-Kilns; and I do hereby declare that the following is a full and exact description of the same, reference being had to the accompanying drawings, and to the letters of reference marked thereon.

10 This invention consists, mainly, in providing a kiln of suitable construction with a proper discharge-opening at its lower end adapted to permit the removal of the finished charcoal, and a proper supply-opening at its upper end 15 adapted to permit the introduction of fresh supplies of wood, by means of which the kiln is made continuous in its operation.

In the drawings, Figure 1 represents a side elevation of my improved kiln; Fig. 2, a central vertical sectional elevation, and Fig. 3 a partial plan view, of the same.

To enable others skilled in the art to make and use my invention, I will now proceed to describe fully its construction and manner of 25 operation.

A represents the kiln, which may be constructed generally in the usual well-known or any other proper manner, but is preferably extended in a vertical direction to obtain greater 30 height than usual, as shown.

a a represent openings at the bottom of the kiln, by means of which a cart or other receptacle for the charcoal may be placed below the discharge-opening of the kiln, hereinafter 35 referred to.

a' a' represent proper openings in the top of the kiln, through which the wood may be introduced and the fire lighted.

a² a² represent proper doors, by means of 40 which these openings may be tightly closed when desired.

B represents a wrought or other metal piece, consisting preferably of an inverted hollow frustum of a cone with double walls, which is 45 built into the kiln near its lower end, for the purpose of serving as a discharge-chute.

b represents an air-supply pipe, communicating at one end with a blower or other proper apparatus for forcing air, and at the other 50 with the interior chamber, x, of the casting B, as shown.

b' represents a corresponding pipe, opening

at its lower end into the chamber x of the casting B, which extends upward to the annular pipe b², surrounding the kiln near its upper 55 end, as shown.

b³ b³ represent a series of branch pipes leading from the annular pipe b² into the kiln, each of which is provided with a proper regulating cock, b⁴, as shown.

C C represent doors of any proper construction, by means of which the upper opening into the chute or casting B may be closed, or partially closed, if desired. These doors consist, preferably, of semicircular flaps c, secured 65 to the centrally-located transverse shafts c' c', the ends of which latter extend through the walls of the kiln, and are provided with counterbalance-weights c² c², serving ordinarily to hold them in a closed position.

D D represent doors of any proper construction, by means of which the lower opening of the chute is closed. These consist, preferably, of rectangular flaps adapted in size to close the discharge-opening of the chute, having corresponding form, which are provided with counterbalance-weights d d, serving ordinarily 75 to hold them in a closed position.

E represents an annular pipe surrounding the kiln some distance below the similar pipe b², which communicates with the interior by a system of branch pipes, e e, having proper stop-cocks, e' e', and with the condenser by a main, e².

The operation is substantially as follows: 85 The kiln is first filled with charcoal to about the line y y, and then with wood the remaining distance, with the exception of a central space, which is left for lighting the fire, which operation may be performed by introducing 90 the lighted material through one of the openings a'. The latter operation having been performed and the doors tightly closed, air is admitted, through the pipe b, casting B, and pipes b' b² b³, to the interior of the kiln. 95 By means of the incoming air-current the smoke and products of combustion are forced through the pipes e E e² to the condenser, where the valuable portions are secured.

When the proper result has been obtained, 100 this being known by practice and the usual indications, the lower doors of the chute are opened and the charge contained therein discharged into a cart or other proper receptacle.

These doors then being closed, the upper doors of the chute are opened to permit a second charge to descend into the chute. The upper portion of the kiln is then provided with fresh supplies of wood.

As the charcoal descends the fire descends with it, but again works its way up toward the line of the air-inlets, this being its constant tendency. The charcoal received into the chute is there held until it becomes partially cooled, this result being hastened by the action of the air-current passing about the chute.

If desired, water also may be introduced in place of the air to hasten the cooling action.

When the water is introduced the active air-blast, of course, is suspended.

The operation of the kiln, it will thus be understood, is continuous, the finished charcoal being removed at intervals from the bottom and fresh supplies of wood inserted at the top.

It will be observed that the air-inlet is located above the smoke-outlet, from which ar-

rangement it follows that the fire remaining below the air-inlet is deprived of oxygen, and is consequently smothered, the air-current passing downward containing only the products of combustion.

Marked advantages result from the use of this kiln, the heat of the kiln always being retained and utilized, instead of being lost at each discharge, as usually occurs.

Having thus fully described my invention, what I claim as new, and desire to secure by Letters Patent, is—

The chute B, having the weighted doors arranged one above the other in a vertical plane, as described.

This specification signed and witnessed this 16th day of August, 1877.

WILLIAM A. MILES.
